CLAIM

The ornamental design for a iron-type golf club, as shown and described.

DESCRIPTION

FIG. 1 illustrates an angled, rear perspective view of a golf club head that shows an apex-like portion within a cavity pad and a convex shaped perimeter weight;

FIG. 2 illustrates a rear perspective view of a golf club head that shows an apex-like portion within a cavity pad and a convex shaped perimeter weight;

FIG. 3 illustrates an angled, rear perspective view of a golf club head that shows a cavity pad and a convex shaped perimeter weight;

FIG. 4 illustrates an angled, bottom perspective view of a golf club head that shows a cavity pad and a convex shaped perimeter weight;

FIG. 5 illustrates an angled, rear perspective view of a golf club head that shows an apex-like portion within a cavity pad and a convex shaped perimeter weight;

FIG. 6 illustrates an angled, side perspective view of a golf club head that shows an apex-like portion within a cavity pad and a convex shaped perimeter weight;

FIG. 7 illustrates a top perspective view of a golf club head that shows a cavity pad a convex shaped perimeter weight;

FIG. 8 illustrates a rear perspective view of a golf club head that shows an apex-like portion within a cavity pad and a convex shaped perimeter weight; and,

FIG. 9 illustrates an angled, side perspective view of a golf club head that shows a cavity pad and a convex shaped perimeter weight.

The broken, dashed lines shown in the various figures depicting embodiments of the invention are included for the purpose of illustrating environment and do not form any part of the claimed design.
